UNITED STATES PATENT OFFICE.

ERNST ZILLESSEN, OF PASSAIC, NEW JERSEY.

DYEING APPARATUS.

No. 813,478.

Specification of Letters Patent.

Patented Feb. 27, 1906.

Application filed March 25, 1905. Serial No. 251,991.

To all whom it may concern:

Be it known that I, ERNST ZILLESSEN, a subject of the German Emperor, residing at Passaic, New Jersey, have invented certain new and useful Improvements in Dyeing Apparatus, of which the following is a clear, full, and exact description.

The object of this invention is to provide apparatus for dyeing which will be economical in the use of dyeing solution and dyestuff and give to the cloth the proper shade and luster, with ease of manipulation of both cloth and dye-bath.

In carrying out this invention I provide a plurality of trays, preferably shallow pans, and I lead the cloth first through one tray and then another. The trays are filled with a dyeing solution, preferably from a circulating system comprising piping and a suitable pump. The trays may be supplied with the dye-bath in any suitable way; but I prefer to feed each one separately from a common supply-pipe and to provide a separate overflow from each tray or pan to the circulating means. I preferably provide each pan with a dam, which may be an ordinary baffle-plate, to maintain the level of the bath. Each tray is preferably supplied with rollers or guides to hold the fabric off the floor of the tray. Rollers may be supplied for squeezing out the surplus dye-bath from the fabric as it comes from each tray. Tensioning-rollers may be supplied for keeping the cloth taut within the trays, and preferably they will be so shaped as to give a sidewise stretch to the material as it passes over them to keep the cloth flat. To economize in room, I prefer to superpose the trays and preferably feed the dyestuff to each tray from a common supply-pipe by individual pipes. When the feeding system is a circulating one, I use a pumping means for keeping up the circulation. In order to keep up the required density of the dye-bath, I from time to time insert concentrated dyestuff into the system, preferably before the bath has reached the pump, so that the feed-pump may thoroughly mix it into the bath.

As will be obvious from the claims, my invention is not limited to that embodiment illustrated in the drawings or specifically described hereinafter; but the constructions and arrangements may be varied without departing from my invention as set forth in said claims.

In the drawings, which show the preferred form of my invention, Figure 1 is a sectional

diagrammatic view of apparatus of my invention, and Fig. 2 is a detail view of one of the stretching-rollers.

In my preferred construction the trays 3 are superposed one above another above a receiving-tank 1 and at a lower level than a feed-tank 2. The tanks 1 and 2 are connected by pipes 13 and 14, which are themselves joined by a pump 9. From the tank 2 I lead preferably a single feed-pipe 15 and tap off from it at suitable intervals with pipes 16, each adjacent pipe 16 preferably leading to opposite ends of adjacent trays. Each tray 3 is preferably provided with a dam or baffle-plate 4 near one end, preferably at the end opposite the inlet of the pipe 16, near which plate 4 an outlet-pipe 18 is located, which connects with a pipe or pipes 17, adapted to lead their contents to the receiving-tank 1.

Guide-rollers 5 are located within the trays to support and hold the fabric off the bottom or tray floor, while squeezing-rollers 6 (which I prefer to also use to draw the cloth through the trays) are located at one end of each tray to express the surplus dye solution from the cloth as it emerges from the tray. A roller 19 may be located at the end of the tray opposite the squeezing-roller, if desired.

At a convenient point adjacent to the ends of two trays I preferably locate a tensioning-roller 7, preferably formed, as shown in Fig. 2, with a reverse helical surface. A spring 8 or other tensioning means may be attached to said roller to give a longitudinal tension to the cloth 20, while the peculiar form of the surface serves to keep it spread sidewise by imparting a sidewise pushing effect from the center to the cloth.

At a convenient point within the circulating system of pipes and tanks I prefer to locate a means for inserting dyestuff into the dye-bath. I prefer to select the pipe 13 as this point and to lead the dyestuff by a pipe 12, having a valve 11 leading from a container 10, holding highly-concentrated dyestuff in the liquid form; but such liquid form and the specific means for inserting the dyestuff may not be essential. By inserting it at the point indicated the feed-pump 9 acts also as a mixing means for thoroughly mixing it in the dye-bath.

In operation I first supply sufficient dye-bath in quantity and density to the trays and tanks and then pass one end of a roll of cloth successively through the trays in the following course, first over roller 19 of the lower-

most tray, then under roller 5 at the left of the tray, over the central roller 5 at the left of the tray, over the central roller 5 and under the right-hand roller 5, then to the 5 squeezing-rollers, and then over the tension-roller 7 to the roller 19 of the next higher tray, through which the cloth passes in reverse direction of travel. The direction is therefore changed as the cloth passes through adjacent 10 trays, which trays in the example shown herein receive the dye-bath at the end opposite to the entry of the cloth.

I claim as my invention—

1. Apparatus for dyeing comprising a series of relatively shallow open superposed dyeing-trays and means for passing a piece of cloth successively through the trays of the series, and means for supplying dyeing liquid to the trays.

2. Apparatus for dyeing comprising a series of open superposed dyeing-trays and means for passing a piece of cloth successively through the trays of the series, in combination with means for continuously circulating 25 dyeing liquid through the trays.

3. Apparatus for dyeing comprising a series of open superposed dyeing-trays and means for passing a piece of cloth successively through the trays of the series, in combination 30 with means for continuously circulating dyeing liquid through the trays and means for inserting dyestuff in the circulating dyeing liquid.

4. Apparatus for dyeing comprising a series of open superposed dyeing-trays and means for passing a piece of cloth successively through the trays of the series, means for circulating dye liquid comprising a pump, and means for inserting dyeing material comprising 40 piping leading to the circulating system on that side of the pump from which the liquid is fed to it.

5. An apparatus for dyeing comprising a plurality of open superposed dyeing-trays, means for passing the cloth successively through said trays, and means for feeding the dyeing liquid to each tray independently of the others and an outlet from each tray.

6. Apparatus for dyeing comprising a plurality of superposed dyeing-trays, means for feeding the dyeing liquid through the trays and means for passing the cloth successively through the trays in combination with a continuous circulating system for the dye-bath.

7. Apparatus for dyeing comprising a plurality of dyeing-trays, means for passing cloth successively through said trays, and means for feeding the dyeing liquid to each tray independently of the others at the end 55 of said trays at which the cloth emerges, and an outlet from each tray at the other end thereof, whereby the flow of said liquid through said tray is contrary to the movement of said cloth therethrough.

8. An apparatus for dyeing comprising a 65 plurality of dyeing-trays, means for passing cloth successively through said trays, and means for feeding the dyeing liquid to each tray independently of the others, and an outlet from each tray, and one or more rollers 70 over which said cloth passes adapted to spread said cloth.

9. An apparatus for dyeing comprising a plurality of dyeing-trays, means for passing cloth successively through said trays, and means for feeding the dyeing liquid to each tray independently of the others, and an outlet from each tray, and one or more tension-rollers over which said cloth passes adapted 75 to spread said cloth.

10. Apparatus for dyeing comprising a plurality of superposed dyeing-trays, means for feeding the dyeing liquid through the trays, means for passing the cloth successively through the trays, and a dyestuff-container 80 provided with valved piping leading to said feeding means.

11. Apparatus for dyeing comprising a plurality of superposed trays, a tank above them and piping from the tank to the trays, 90 a receiving-tank, piping from the trays leading thereto, means for feeding cloth first through one tray and then another, means for feeding the liquid from the receiving-tank to the feed-tank and means for inserting dye- 95 stuff into the liquid during its feed.

12. Dyeing apparatus comprising a feed-tank, a receiving-tank, a circulating pump and piping between them, supply-piping leading from said feed-tank, a number of 100 superposed trays, each having a spring-roller and squeezing-rollers mounted adjacent to one end and rollers within each tray adapted to support the cloth, an inlet to each tray from the supply-piping and an outlet from 105 each tray to the receiving-tank.

13. Dyeing apparatus comprising a number of trays, and means for passing cloth through the trays successively, means for stretching the cloth lengthwise and sidewise 110 as it is passed therethrough, in combination with means for continuously passing a dyeing liquid through said trays.

14. Dyeing apparatus comprising a number of trays, means for passing cloth through 115 the trays successively, in combination with supply-piping and a pump for continuous circulating dyeing liquid through the trays, and means for inserting dyestuff into the liquid as it comes from the pans whereby the 120 same dye-bath may be used indefinitely.

Signed at New York, N. Y., this 21st day of March, 1905:

ERNST ZILLESSEN.
